INTERCHANGEABLE ATTACHMENT

Bernard Darvie, Irving Darvie, and Samuel Darvie, New York, N. Y.

Application July 12, 1938, Serial No. 218,738

6 Claims. (Cl. 63—1)

This invention relates to interchangeable attachments, particularly to those adapted for use with ornamental articles such as dress clips, shoe clips, belt buckles, brooches and the like.

5 It is primarily within the contemplation of our invention to enable an ornamental article, or a pair of such articles, to be conveniently employed for various purposes by the expedient of interchangeably applying thereto simple fastening elements. Cognizance is taken of other ornamental attachments of this general character, but most of such devices are not only relatively expensive and intricate to handle, but are also commonly encumbered with certain permanently 10 affixed fastening elements which not alone detract from the appearance of the ornament, but also add considerably to the weight thereof. It is hence one of the objectives of our invention to obviate these shortcomings by presenting a 15 relatively simple device wherein all the fastening elements, for whatever purpose they may be employed, are detachable, so that only a single type of fastening element is secured to the ornament at one time. The arrangement is such 20 as to reduce both the weight and bulk of the ornament, and eliminate any unsightly fastening elements that might otherwise be visible, the accomplishment of this purpose constituting another one of the objects of our invention.

25 30 It is a common practice to secure fastening elements to an ornament by means of soldering, a method which is known to have certain disadvantages. For example, the employment of heat during the soldering process is apt to cause certain 35 spring elements to lose their temper, and will frequently damage the ornament proper; and in the case of a gold-plated ornament, the application of heat for soldering purposes will often remove a portion of gold. There is also 40 the danger that the solder will flow around and upon the spring of the catch or pin element, thereby rendering such spring ineffective. It is 45 hence another of our objectives to enable the fastening elements to be attached to the ornament without the necessity of any soldering operation whatsoever. And in this aspect of our invention, another object is to enable broken or defective fastening elements to be readily replaced without any heat or soldering processes.

50 55 Other objects, features and advantages will appear from the drawings and the description hereinafter given.

In the drawings,

Figure 1 represents a disassembled perspective view of the elements of a belt buckle containing

our invention, the view showing the rear portions of the main ornament buckle members, and illustrating one of the adjustable belt bars and the hook element with fragments thereof removed.

Figure 2 is a perspective view of a dress clip 5 attachment containing the male fastening element constituting part of our invention, a portion of the structure being removed for clarity.

Figure 3 is a perspective view of certain of the fastening elements of our invention employed in 10 a pin brooch attachment.

Figure 4 is a perspective of one of the fastening elements of our invention as applied to a shoe clip.

Figure 5 is a rear plan view showing the elements of Figure 1 assembled to form a belt buckle unit.

Figure 6 is a rear plan view of a pair of the main ornament members of Figures 1 and 5 showing on each the dress clip attachment of 20 Figure 2, thereby illustrating a pair of dress clips.

Figure 7 is a rear plan view of the two main ornamental members of Figures 1 and 5 assembled together with the attachment of Figure 3 to form a brooch, and

Figure 8 is a rear plan view of a pair of shoe clips embodying the main ornament members of Figures 1 and 5 in combination with shoe clips of the type illustrated in Figure 4.

In the drawings, and particularly Figure 1 30 thereof, the main ornament members 10 and 11 contain thereon sockets 12 and 13 respectively, each of these being adapted to receive any one of several various fastening elements, as will more clearly appear from the description hereinafter given. The said members 10 and 11 are preferably of identical structure, so that only a single form of member need be fabricated for the various purposes for which pairs of such members may be employed, in accordance with 35 the teachings of this invention, and the said sockets 12 and 13 are also of similar construction, being adapted to receive male fastening attachments, such as those on the hook and eye elements 14 and 15, respectively.

The socket 12 contains on one side thereof a long channel or guide 16 and on the other side a relatively short channel or guide 17 extending only a portion of the way along the length of the socket. A wall of the short channel,—the wall 18 in the drawings illustrated,—tapers down at one end 19 thereof to the base 9 of the socket, thereby forming an inclined wall leading up to a notch 20. The rear of the socket contains an upwardly extending wall 21 forming a stop. The 50 55 45 50 55 55

socket 13 has similar elements, to wit, channels or guides 22 and 23, a wall 24 with an inclined portion 25, a notch 26, a stop 21a and a base 9a. It should also be noted that the channels 17 and 23 begin at points remote from the notches 20 and 26 respectively, for reasons which will hereinafter appear.

The male fastening elements 14 and 15 contain the slides 27 and 28 respectively, preferably made of spring material, the lateral sides of said slides containing arms or spring tongues 29 and 30 respectively, the said tongues containing laterally extending extensions 31 and 32 respectively, preferably at a level slightly higher than that of the upper surfaces of slides 27 and 28. In Figures 1 and 5, the hook portion 33 is adapted to engage the eye portion 34 in conventional manner so as to enable elements 14 and 15 to serve as cooperative elements of a belt buckle when operatively positioned in place.

In assembling the elements 14 and 15 upon the main ornaments 10 and 11, the operations are identical, and hence only the method of assembling element 14 will be described. The rear edge 35 of this element (see Figure 1) is inserted within the channel groove 36 of the guide 16, and slidably moved rearwardly into socket 12 upon the base 9 thereof, the lateral edges of the slide 27 slidably engaging the vertical walls of the guides. During the said sliding movement, the extension 31, upon engaging the inclined wall 19, will be yieldably moved upwardly, inasmuch as the tongue 29 which carries said extension is of spring material. Upon a continued rearward movement of the slide, the extension 31 will eventually snap into the notch 20 to hold the entire fastening element 14 in place within the socket. In this position, the slide 27 is held against upward movement by the channels or guides 16 and 17, against forward movement by the forward wall of notch 20, and against rearward movement by the rear wall of notch 20 and the stop 21.

When the fastening element 15 is slidably positioned into place, precisely in the manner of element 14, the hook and eye elements of the belt will be attached to the complementary buckle members 10 and 11 for cooperative attachment, as is illustrated in Figure 5. It will also be noted that in their assembled relation the ornament members 10 and 11 have their respective socket members oppositely positioned, an arrangement which obviously results from the identical construction of said members.

The belt bars 37 and 38 are of telescopic arrangement, the hollow elements 39 and 40 thereof being shown to contain holes 41 and 42, respectively, with which the terminal portion of the spring tongue 44 (Figure 1) is in operative engagement to adjustably and frictionally hold the said telescopic elements in place. The said bars contain the male fastening slide elements 45 and 46 respectively, as well as the spring tongues 47, 48 and extensions 49 and 49a respectively, similar in structure to the analogous elements of the hook and eye members 14 and 15 previously described. In the particular embodiment shown in Figure 1, the said belt bars also contain, oppositely disposed with respect to said slide elements 45 and 46, the base members 50 and 51 respectively. It is however, also within the contemplation of this invention to employ, if desired, slide elements similar to 45 and 46 instead of the said base members. It will be noted that the slides 75 45, 46 and bases 50 and 51 are of greater width

than the vertical walls 66, 67, 68 and 69 of the belt bars, leaving the lateral margins of the slides and bases free and unobstructed for sliding purposes as will more clearly hereinafter appear.

The main ornament members 10 and 11 each 5 contains a second set of sockets adapted to receive the slides 45 and 46 and the bases 50 and 51. The sockets 52 and 53 are similar in general construction to the sockets 12 and 13, containing the channels 54 and 55, and 56 and 57 respectively, 10 as well as the notch 58, inclined wall 59, and corresponding parts 60 and 61 respectively. The bases 62 and 63 of these portions are however partly cut out so as to reduce the visible portion of the sockets 52 and 53 which might otherwise 15 be seen through the apertures 64 and 65.

Inasmuch as the assembly of the belt bars 37 and 38 are identical, only the assembly operation of the bar 37 will be described. The unobstructed lateral edges 70 of the slide 45 are inserted within the grooves of the channels 54 and 55, and the edge 71 of base 50 is simultaneously inserted within the grooves of the channels 72 and 73 of socket 56a. The bar is then moved in the direction of the arrows (see Figure 1) until the extension 49 is locked within the notch 48 in the manner aforesaid. Hence when both members 37 and 38 are assembled in place in this manner, they will constitute part of the belt buckle shown in Figure 5 and adapted to operatively receive a 30 loop of the belts therethrough.

In detaching the said fastening elements from their assembled positions, the operation as applied only to member 14 and the socket 12 will be described as all the other fastening elements 38 are similarly detached. The operation is exceedingly simple, consisting merely of elevating the extension 31 until it is out of the notch 20 and then slidably manipulating the member forwardly, the base 27 readily sliding within the channels 16 and 17, inasmuch as there are no obstructions to such movement. In this manner, the male fastening element is removed from the socket which is now in a position to receive another fastening element, if desired, as will be 45 hereinafter set forth.

Note should be taken that the forward edge 74 of channel 17 (see Figures 1 and 5) is remote from the notch 20. This arrangement gives sufficient leverage to the spring tongue 29 so that it 50 can be readily moved upwardly during the disassembling operation as above described, particularly inasmuch as the portion 75 of said tongue is engageable with the guide 17 substantially at the region of edge 74. If the edge 74 were closer to 55 the notch 20, obviously the spring tongue 29 would have a shorter lever arm and hence would be more difficult to be moved upwardly.

In Figure 2 is shown a dress clip containing a pivotally mounted member 76 of conventional 60 form, said clip, however, being operatively attached to a male slide element 77, similar to the slide elements hereinabove described, containing a spring tongue 78 and an extension 79. This member can hence be detachably secured to 65 ornament members such as 10 and 11, simply by sliding the member 77 into the socket, in the manner hereinabove described. This will produce an arrangement shown in Figure 6, which illustrates the form of clip member of Figure 2 as applied to 70 the two ornament members 10 and 11. Obviously this dress clip ornament can be used either singly or in pairs.

The shoe clip shown in Figure 4 contains a clip portion 80 of conventional structure mounted 75

upon a slide 81 similar to the slides hereinabove described containing a spring tongue 82 and extension 83. The slide can be readily inserted within the socket of either ornament members 10 or 11 to form a shoe clip similar to the pair shown in Figure 8. It is, of course, obvious that the device of Figure 4 is operatively applied upon the upper portion of a shoe by compressing the clip portion 80 towards the slide 81.

10 In Figure 3 is shown another embodiment of my invention, the pin bar 84 being attached by means of the straps 85 and 86 to the slide elements 87 and 88 which are secured together by the connecting bar 89. These slide elements are similar to those hereinabove described, containing spring tongues 90 and 91 respectively, and extensions 92 and 93 respectively. This device is attached to two ornament members in the manner shown in Figure 7, both said ornament members being in contiguous juxtaposition with the slides 87 and 88 in operative engagement with the sockets 12 and 13.

15 It is thus apparent that the ornament members 10 and 11 can readily be employed for various purposes, as above set forth, by the simple expedient of interchangeably applying the various fastening elements to the sockets on these members in the manner described. The ornament members in themselves carry nothing more than 20 socket members, and hence are not burdened with excessive weight or bulky and unsightly fastening elements permanently affixed thereto. And inasmuch as the fastening elements are slidably positioned in place, no soldering whatsoever 25 need be done. Should a fastening element become defective or broken, all that need be done is to have a new one obtained without in any way mutilating the ornament member which generally is the most expensive part of the device.

30 40 It is of course understood that the various embodiments above described and shown in the drawings are illustrative of our invention and not employed by way of limitation, inasmuch as numerous changes and modifications may be 45 made within the scope of the appended claims without departing from the spirit of this invention.

What we claim is:

1. In a replaceable attachment, a female socket member and a male fastening attachment adapted for detachable engagement therewith, said socket member containing a base, lateral guides, an elevated wall extending along a lateral edge of the base in unobstructing relation to the 55 medial portion thereof and containing a notch therein, said fastening attachment containing a slide and a spring tongue at a lateral side thereof and in unobstructing relation to the medial portion thereof, the slide being slidably movable upon said base between said guides, the tongue containing an extension thereon adapted to engage said wall during the operative assembling movement of the slide upon the base, whereby the tongue is raised and yieldably maintained in an elevated position until released therefrom when the extension reaches and enters said notch, the 60 said extension overlapping and extending beyond the adjacent lateral edge of the base and the said wall whereby it could be readily grasped for manual manipulation.

65 70 75 2. In a replaceable attachment, a female socket member and a male fastening attachment adapted for detachable engagement therewith, said socket member containing a base, guiding means, a stop at the rear of the base, and a wall extend-

ing perpendicularly from a lateral edge of the base and containing a recessed portion, said fastening attachment containing a slide and a spring arm at a lateral side thereof, the slide being slidably movable upon said base and operatively engageable with said guiding means and said stop, the spring arm having a portion thereof extending outwardly and adapted to engage said wall during the operative assembling movement of the slide upon the base, whereby the arm is raised and yieldably maintained in an elevated position until released therefrom when the wall-engaging portion of said arm reaches and enters said recessed portion, the socket member and attachment being so proportioned that the said wall-engaging portion of the arm is positioned within the said recessed portion when the slide is in engagement with the said stop and in overlapping relation to the adjacent lateral edge of the base.

20 25 3. The combination according to claim 2, wherein the said wall has its forward edge tapering down to the base whereby the spring arm will be gradually elevated upon coming into operative engagement therewith.

25 30 35 4. In a replaceable attachment, a female socket member and a male fastening attachment adapted for detachable engagement therewith, said socket member containing a base, two guides of channel-like structure at opposite lateral edges of the base, one of the guides being shorter than the other, an elevated wall extending along the base at the edge thereof at which the shorter of said guides is positioned and substantially in line therewith, said wall containing a notch therein, said fastening attachment containing a solid flat slide entirely in one plane and a spring tongue at a lateral side thereof, the slide being slidably movable upon said base between said guides and said wall, the tongue containing an extension thereon adapted to engage said wall during the operative assembling movement of the slide upon the base, whereby the tongue is raised and yieldably maintained in an elevated position until released therefrom when the extension reaches and enters said notch, the said extension overlapping and extending beyond the adjacent lateral edge of the base and the said wall whereby it could be readily grasped for manual manipulation.

50 55 60 65 70 75 5. In a replaceable attachment, a female socket member and a male fastening attachment adapted for detachable engagement therewith, said socket member containing a base, two guides at opposite lateral edges of the base, an elevated wall extending along the base at one edge thereof and substantially in line with the guide positioned at that edge, said wall containing a notch therein remote from the forward portion of said last-mentioned guide, said fastening attachment containing a slide and a spring tongue at a lateral side thereof, the slide being slidably movable upon said base between said guides, the tongue containing a transverse extension thereon overlapping the adjacent lateral edge of the base and adapted to engage said wall during the operative assembling movement of the slide upon the base, whereby the tongue is raised and yieldably maintained in an elevated position until released therefrom when the extension reaches and enters said notch, the tongue being of a sufficient length to be in engagement with the said forward portion of the adjacent guide to enable it to be yieldably actuated upon manual manipulation.

75 80 85 90 95 6. In an ornamental attachment, a main orna-

ment member containing on the rear side thereof a female socket member, and a removable male fastening attachment adapted for detachable engagement therewith, said socket member containing a base, guiding means, and a wall extending perpendicularly from a lateral edge of the base and containing a recessed portion, said fastening attachment containing a solid flat slide entirely in one plane, and a spring arm at a lateral side thereof, the slide being slidably movable upon said base and operatively engageable with said guiding means, the spring arm having a portion thereof extending outwardly and adapted to engage said wall during the operative assembling move-

ment of the slide upon the base, whereby the arm is raised and yieldably maintained in an elevated position until released therefrom when the wall-engaging portion of said arm reaches and enters said recessed portion, the said wall-engaging portion of the arm being in overlapping relation to and extending beyond the adjacent lateral edge of the base and the said wall; said fastening attachment also containing independent fastening means associated with the slide.
